LADDER

Ambrose Bianchi, San Francisco, Calif.

Application May 6, 1946, Serial No. 667,571

2 Claims. (Cl. 228—21)

1

This invention relates to step ladders of the folding type in which a rung portion and a prop portion are hinged together so that they may be folded to occupy less space when stored or transported than when in use. The prop portion referred to includes two supporting legs spread apart in divergent relation from top to bottom to stabilize the ladder when it is in use.

One of the objects of my invention is to provide a folding ladder, the rung portion and the prop portion of which may be extended and collapsed in the direction of their lengths, so that not only may the ladder be stored and transported in small spaces, but it may be used in places having comparatively little or great vertical clearance or headroom.

Another of the objects of my invention is to provide, in a ladder having diverging legs in the prop portion, for adjustments of the lengths of the supporting legs so that they may be made shorter than the rung portion of the ladder whereby the ladder may be positioned on a stairway, with the rung portion on a lower step and the supporting legs footed on a third or fourth step thereabove.

Another object of the invention is to provide, in a ladder having extensible and collapsible rung sections and supporting legs, for the securing of the rung sections in a length less than the extended length of the prop legs so that the rung portion can have footing on a higher step and the prop legs can be extended to footings on steps lower than the footings of the rung portion. In this way the ladder can be approached from the head end of a flight of stairs and the ladder can be used on flights having relatively low ceilings.

These and other objects and advantages are attained by the construction and arrangement of parts as described in the following specification wherein reference is made to the accompanying drawings, in which:

Fig. 1 is an isometric view of my new ladder showing the leg sections and the rung sections fully extended;

Fig. 2 is a view of the front of the ladder with the rung and prop sections in fully collapsed relation and the rung portion and prop legs folded together so that the ladder occupies a minimum of space;

Figs. 3 and 4 are elevations of the supporting leg sections in fully extended and collapsed relations respectively;

Fig. 4a is an enlarged fragmentary view of a detail;

2

Figs. 4b and 4c are fragmentary sections at IVb—IVb and IVc—IVc, respectively, of Fig. 4;

Figs. 5, 6 and 7 illustrate details of the telescoping members employed in both the leg sections and the rung sections;

Figs. 8 through 12, inclusive, are diagrammatic views illustrating the construction, and the various phases of the operation, of the elements governing the extension and collapsing of the rung sections in extended relation; and

Fig. 13 is a similar view illustrating the construction and operation of the elements governing the extension and collapse of the prop section.

15 The ladder shown in the drawings comprises a rung portion 10 and a supporting prop portion 12, hinged for folding and unfolding to a platform 14 by pivot screws 16 and hinge 18 (Fig. 3). Unfolding or spreading of the prop and rung 20 portions is limited by a folding linkage 15 well known in the art. The pivot screws 16 extend through angle brackets 20, secured to platform 14 by screws 22, and into the wood of upper prop sections 38. Hinging at 18 may be provided by 25 a conventional T hinge, the bar 26 of which is securely fastened to the platform 14 and the strap 28 being provided with a vertical slot 30 in which a pin 32 is free to slide. Pin 32 pivotally connects braces 34 of the upper prop sections 38 which are pivoted at their lower ends 30 as shown at 36 in Fig. 4. The prop sections 38 diverge downwardly as shown and are provided on their outer sides with longitudinal metal rails 40 forming a part of the telescoping mechanism 35 of the prop.

The lower part of the supporting prop is formed by the prop members 42 joined near their lower extremities by the cross bar 44 centrally provided with a vertical slot 46 (Fig. 4a) in which a pin 48 pivotally connecting the braces 50 is free to slide. Braces 50 are pivoted as at 52 at their upper ends. The telescopic rails 40 on the upper leg section 38 are received in telescopic channels 54 in the lower prop sections 45 42 (see Fig. 5). Means to be described govern the operation of these telescoping members.

The pivotal linkages of the braces 34 at 32 and braces 50 at 48 permit the divergent legs to telescopically slide with complete freedom, the sliding downwardly of pin 48 in slot 46 accompanying the movement of leg stringers 38 downwardly because this movement draws the upper ends of leg stringers 42 closer together. In the same 55 movement the lower ends of leg stringer sections

38 move farther apart and the pin 32 moves toward the lower end of slot 30.

The interengaging members providing telescopic engagement between the sections 38 and 42 of the prop member are illustrated in Figs. 5, 6 and 7. Similar structure provides telescopic interengagement between the sections of the rung portion later to be described. The telescopic engagement between the prop sections 38 and 42 is provided by a wear plate and rail bracket 37 providing the wearing surfaces 37a and 37b defining with angled bracket portions 37c two longitudinal slide bearing grooves 37d in which there are reciprocatively received the longitudinally extensible bearing portions 61a of a channel strip 60 secured by screws 63 to prop member 42 with the channel interlock housing part 61b received by a longitudinal groove 61c in member 42. The interlock housing parts 61b includes longitudinal side walls 62 and 72 provided with dog control ports, as at 74 and receives the rail portion 40 to be more specifically described later.

The plate forming rail 40 and the bottom 61d of the housing 61b are spaced apart to provide a space 63 within which dogs carried by rail 40 for cooperation with openings 74 are disposed as will presently be described in detail.

The interlocking arrangement provided within the channel and associated with space 63 (Fig. 5) for both the prop and the rung portions of the ladder are explained with the aid of Figs. 8 through 13, in which for Fig. 13 only the side walls 62 and 72 of the housing 61b, and portions of the rail 40 with dogs, etc., are shown, and for Figs. 8 through 12 the corresponding side walls 62' and 72' and rail 40' with its dogs are shown.

The rung portion 10 of the ladder comprises, as shown in Fig. 1, a series of telescopically interengaged sections 78, 80, 82 and 84. The sections 78, 80 and 82 each include a single horizontal rung 78a, 80a, and 82a, respectively, extending between parallel ladder-leg sections 78b, 80b and 82b.

The top section 84 may be provided with two or more rung sections 84a and supports the platform 14.

The sections 78 to 84 telescope with relation to each other to enable them to slide to the compact positions illustrated in Fig. 2.

The telescoping members are connected by rails and channels constructed as shown in Figs. 5, 6 and 7 as previously described and in association therewith there are certain latching elements determining the manner of holding and releasing the rung sections for extension and collapse. These elements and their operations are shown in Figs. 8 through 12.

An understanding of the operation of the latching mechanism will be facilitated by a description of its function. In extending section 84 with respect to section 82, the extension is to a length greater than the actual separation when in position for use. After such over-extension, section 84 is permitted to fall back into the position for use, in which it is automatically retained by locking dogs hereafter described. These dogs serve their holding function until the section 84 is required to be collapsed, which is accomplished by first extending section 84 from section 82 as far as it will go. This effects the release of the locking dogs and the section 84 may slide into collapsed relation. The channels 60' are carried by the lower sections and the rails 40 are carried by the upper sections of each pair of telescoping sections. This operation is diagrammatically

illustrated in Figs. 8 through 12 in which the rail 40' is shown in several positions as it slides between the wall's 72 of the channel.

Fig. 8 shows the positions assumed by the parts when the rung sections of the ladder are collapsed. Consider the rail 40' as the moving member and the channel as fixed. A dog 86 pivoted to the rail 40' will upon slight movement of the rail (leftward in Fig. 8) be released for counterclockwise rotation about its pivot 88 as its heel 90 comes in registry with hole 92. Toe 94 remains engaged in hole 96 until by further movement dog 86 is rotated to the position shown in Fig. 9, and toe 94 is drawn out of hole 96 against the clockwise urgency of spring 98. In this relation the rail 40 and dog 86 travel until stopped in the over-extended position illustrated in Fig. 10 by the over-extension-stop dog 100 which engages the edge 102 of a hole 106 suitably located for the purpose. Dog 86 remains in this position with its toe 94 biased against wall 62' until the movement of rail 40' is reversed sufficiently to permit toe 94 to fall into hole 104. With this, further continued movement in reverse or collapsing direction of the rail 40 is prevented and the two sections of ladder rungs are now in usable extended relation, held so by the dog 86 in holes 94.

Incident to this short reverse movement, the dog 100 is caused to rotate about its pin 108 and slot pivot 101 on rail 40' and to reverse its position, through its engagement with the edge of the dog stop and reversing hole 106, so that in the usable position of Fig. 12, dog 100 is held inactive by the inside surface of wall 72' upon which it slides, being urged clockwise about pin 108 by tension spring 110.

To release the rail 40' for movement rightward of the usable position of Fig. 11, rail 40' is first moved to the left to a position as in Fig. 12, beyond that of Fig. 10, where the toe 94 of dog 86 enters dog release opening 112 and the rail 40' is stopped by fixed stop 114. Dog 100 in this movement slides over opening 106, its straight back 100a engaging with wall 72'. In the Fig. 12 position, dog 86 enters release hole 112 and, upon the next rightward movement of rail 40' dog 86 is permitted to rotate to the position of Fig. 12 under action of spring 98, and to be further rotated clockwise incident to rightward movement when the toe 94 engages the rightward edge of opening 112, the rotation being timed and sufficient to cause the dog to clear the right edge of clearance opening 114. The dog 86 is then held in a position relative to rail 40 similar to that shown in Fig. 8 until again reversed slightly leftward of the Fig. 8 position as previously described.

The over-extension stop dog 100 remains in the same relative position from the Fig. 12 to the Fig. 8 positions, remaining inoperative until, in moving from the Fig. 8 position toward the over-extended position of Fig. 10, it is reversed to operative position when its hook end 116 is biased by spring 110 outwardly through hole 114 and engages the camming surface 118 of hole 114.

The prop members 38 may be extended in any desired degree and maintained in such condition of extension against collapse by dogs 56 (Fig. 13) pivoted by pins 58 secured on the lower (as shown in Fig. 5) surface of the rail 40 within the portion 63 of channel space 54 formed by channel member 60. The side walls 62 of the channels are provided through the greater portions of their lengths with a series of equally spaced openings

64 disposed adjacent the path of movement of the dog 56 as shown in Fig. 13 so that when the dog 56 is in the position shown its engaging tooth 66 is drawn into the corresponding opening 64 by the spring 68 and the rail 40 and leg 38 cannot be moved (rightward in Fig. 13) in the direction of collapse. Thus, the holes 64 and dog 56 provide for holding the legs against collapse in any desired position of adjustment.

Provision is made so that when the ladder is in a partially extended position it may be readjusted to a less extended position, but this may only be done deliberately because the heel 70 of the dog engages the wall 72 of the channel and is prevented from rotating to released position. When the rail 40 has moved leftward (in Fig. 13) into the last hole 64' the rail 40 may be returned to collapsed position. The wall 72 is provided with a release opening 74 opposite a dog engaging and reversing hole 64' so that upon urging the rail 40 rightwardly (in Fig. 13) the dog 56 is turned clockwise about pin 58 so that the tooth 66 is disposed in trailing relation to pin 58 and rides over the holes 64. The leg sections must be fully collapsed before the dog 56 again becomes effective; that is, before it may return to the full line position of Fig. 13. This is effected when the dog has moved to a collapsed position opposite a second dog engaging and reversing hole 64'' in registry with which there is provided an elongated dog-clearance hole 76 in the wall 72, by the action of spring 68 which turns the dog 56 counterclockwise about 58 to the normal position (full line position of Fig. 13). It will be evident, therefore, that the shortening of the extended prop legs requires first a full extension of the legs, a return to the fully collapsed state and a readjustment to the required shorter length. In this way it is insured that the legs cannot be collapsed while the user is on the ladder, the clearance hole 74 being substantially beyond the range of ladder use, which use corresponds to the extent of the holes 64.

With the construction just described, the rung portion of the ladder can be extended to lengths varying as the number of sections individually extended. Thus, with the ladder shown, four dif-

ferent ladder lengths are provided, and the supporting legs 12 can be adjusted to any length greater than its minimum length to accommodate the ladder to inclined footing.

5 I claim:

1. In a ladder having a platform, and having a telescopic ladder section and a prop portion supporting the platform, said prop portion having telescoping sets of downwardly diverging legs, means for bracing said legs relative to each other comprising a brace pivotally connected to each leg part at one end and pivotally and slidably connected to a fixed ladder part at its opposite end.
2. In a ladder having a platform, and having a telescopic ladder section and a prop portion supporting the platform, said prop portion having telescoping sets of downwardly diverging legs, means for bracing said legs relative to each other comprising a pair of angularly related braces pivotally connected one with each of the upper leg parts and slidably and pivotally connected to the platform, a horizontal brace extending between the lower leg parts, and angular braces pivoted 20 one to each lower leg part and slidably and pivotally connected with said horizontal brace.

25 AMBROSE BIANCHI.
